UNITED STATES PATENT OFFICE.

ABBOT AUGUSTUS LOW, OF NEW YORK, N. Y.

DESIGN FOR A BOTTLE.

SPECIFICATION forming part of Design No. 31,179, dated July 11, 1899.

Application filed June 12, 1899. Serial No. 720,297. Term of patent 14 years.

To all whom it may concern:

Be it known that I, ABBOT AUGUSTUS LOW, a citizen of the United States, residing in New York, borough of Brooklyn, in the county of Kings and State of New York, have invented a new and original Design for Bottles, of which the following is a specification, reference being had to the accompanying drawings, forming part thereof.

10 Figure 1 is a plan of a bottle embodying my new design. Fig. 2 is a side elevation thereof; and Fig. 3, a vertical section upon plane of line 3 3, Fig. 1.

15 As shown in the drawings, the leading or material feature of my design consists in the

square shape of the body B, merging into the curved top a, which is made in the form of a flattened cycloidal arch or dome surmounted by the cylindrical neck N, having the peripheral spiral bead s.
